UNITED STATES PATENT OFFICE.

NELSON LITTELL, OF BROOKLYN, NEW YORK.

MOLDING MACHINE

Application filed June 6, 1924. Serial No. 718,915.

This invention relates to molding apparatus of the type in which the sand is forcibly projected into the flask to form the mold.

In machines of this type it is important that the wads of sand be hurled into the flask at a substantially non-variant angle of delivery and it is preferable that they be hurled vertically downward.

To insure vertical delivery of the wads into the flask it is necessary that the delivery end of the machine be movable in a horizontal plane over all parts of the flask or in other words, it is necessary for the projector head to have universal movement in a horizontal plane. Heretofore, this universal movement has been secured by a swinging gib and an arm pivoted at one end to the gib and having the projector head at the other end, the two pivots giving the desired flexibility of movement. With this type of machine it is necessary to feed sand to the machine at a point over the axis of the swinging gib and thence convey it along the gib to a point over the arm pivot and thence along the arm to the projector head, and to provide separate conveying means along the gib and along the arm.

It is one of the objects of this invention to simplify the construction of machines of this type by substituting a pivot and a slide for the two pivots of the prior machines, the beam or beams supporting the delivery end of the machine being mounted so they can be slid back and forth on the slide and swung laterally from side to side on the pivot to secure the desired universal movement.

Another object of the invention is to feed the sand to the machine at a point over the pivot and convey it outwardly along the beams of the machine to the delivery end, in such a way as to use only one conveying means.

A further and very important feature of this invention is the provision of a unitary means for conveying the sand from over the pivot point, where it is fed to the machine, to the delivery end of the machine and there, by the aid of a deflector, hurling it downwardly into the flask with sufficient force to pack the same. In this way the construction of the delivery end of the machine is simplified and the expensive projector head used on prior machines of this kind is entirely dispensed with.

Various other objects and advantages will

appear as the description of the invention proceeds.

Referring now to the drawings which illustrate preferred forms of embodiment of the invention:

Fig. 1 is a side elevation of one embodiment of the machine with parts broken away.

Fig. 2 is a sectional view of the pivot on the line 2—2 of Fig. 1.

Fig. 3 is a sectional view through one of the slides taken on the line 3—3 of Fig. 2.

Fig. 4 is a plan view of the machine with the sand hopper removed.

Fig. 5 is an elevation of the adjustable pulley bearings.

Fig. 6 is a plan view of part of the belt driving mechanism.

Fig. 7 is an elevation of the belt driving mechanism.

Fig. 8 is a side elevation of another form of embodiment of the invention.

Fig. 9 is a sectional view on the line 9—9 of Fig. 8.

Fig. 10 is a partial section on the line 10—10 of Figure 8, in which a further modification is shown.

Fig. 11 is a perspective view of the deflector.

Fig. 12 is a detail view of the compactor.

In the embodiment illustrated in Figs. 1 to 7 the machine is supported upon a mast 1 which rests upon the floor of the foundry. At its upper end the mast 1 supports a pivot 2 which carries a pair of guides 3 through which the beams 4 are slidable back and forth as illustrated in the dash line position in Fig. 1.

At one end the beams 4 carry a projector 5, which may be of similar construction to the projector disclosed in the U. S. Patent No. 1,335,642, issued March 30, 1920, and at the other end a motor 13 is provided by which the rotor of the projector is driven through the motor shaft 14.

To supply sand to the projector the beams 4 are provided near each end with pulleys 8 and 8^a around which the belt 9 travels to carry the sand from the hopper 10, supported upon stays 12 over the pivot 2, to the projector.

The pulley 8 is adjustably mounted in the brackets 7, which are provided with guides 25 along which the bearing blocks 26, for the pulley shaft 27, are adjustable under the influence of the screws 28. The screws

28 may be provided with lock nuts (not shown) for holding the pulley in adjusted position. The pulley 8^a is carried by the stationary brackets 33.

6 To drive the pulley 8^a and the belt 9 the motor shaft 14 is provided with a bevel gear 15 which meshes with a similar gear 17 on the stud shaft 16, which is supported by the bracket 30 and projects through the 10 beam 4. At its outer end the shaft 16 carries a spur-gear 31 which meshes with a gear 24 upon the outer end of the shaft 35 of pulley 8^a, the ratio between gears 24 and 31 being such as to drive the pulley 8^a and 15 belt 9 at the proper speed.

To facilitate swinging the beams 4 and the projector head about the pivot 2, the pivot is mounted upon roller bearings 19 and ball bearings 20 carried in the annular ball races upon the face of the plates 29 as illustrated in Fig. 2. A shield 21 projects downward from the upper plate to keep sand from entering between the plates and getting into the bearings.

25 The guides 3 through which the beams 4 are slidable back and forth are also provided with roller bearings 22 to reduce friction and the underneath part of beams 4 may be provided with replaceable wear plates 32 by which the wear between the beams 4 and the guides 3 can be periodically taken up.

Supporting arms 23 are provided for holding the projector head on the end of 35 the beams and braces 18 keep the beams properly spaced at the ends, the guides 3 being spaced by the braces 34. Each of the braces 18 and 34 are shaped so as to permit the shaft 14 to pass therethrough.

40 In operation, the sand is fed into the hopper 10 and passes through the opening 11 onto the belt 9 which carries it in a continuous stream outwardly along the beams and into the projector casing 5 where 45 the rotor severs the incoming stream into wads and hurls them downward into the flask as described in the said Patent, No. 1,835,642. The projector head is moved over all parts of the flask by sliding the beams 4 back and forth in the guides 3 as 50 illustrated in the dash line position in Figure 1 and by swinging the head laterally from side to side around the pivot 2.

In the embodiment illustrated in Figures 55 8 to 11 the mast 1 carries a similar pivot 2 comprising the annular plates 29, ball bearings 20 and roller bearings 19. In this modification, however, the guides 3 are spaced from the upper plate 29 by the spacing elements 35^a so as to permit one lap of the belt 36 to pass between the braces 34 and the plate 29. In this modification the pulleys 37 and 37^a are carried in the ends 60 of the beams 4, the pulley 37^a being adjustable to keep the belt 36 taut by means

of the projecting guides 38 and set screw 39 in the end of the beams.

The pulley 37 may be driven by the motor 38^a through the agency of a belt 39 or it may be driven by a motor in which the 70 field or armature rotates around a stationary core, the belt being carried directly upon the rotating casing of the motor as illustrated in Fig. 10, wherein the stationary shaft 40 of the core of the motor is 75 carried in the beams 4 and the casing 41 carrying the belt 36 rotates upon suitable bearings on the shaft 40.

The belt 36 is provided at suitable intervals with buckets 42 which carry the wads 80 of sand from the hopper 10, to the pulley 37 and there, by the aid of the deflector 43, hurl them downward into the flask. It is of course understood that the belt is rotated at sufficiently high speed to catch the sand 85 into the buckets 42 in wads and to hurl the wads downward with sufficient force to pack the same densely enough for metal founding.

To prevent the sand from being hurled off the belt before it reaches the discharge 90 end of the deflector, the hopper 10 is provided with an outwardly extending shield 44 which covers the top and projects downward over the sides of the belt as at 45. 95 The deflector 43 also carries a shield 46 which slides within the shield 44 so as to cover the belt in all positions of the machine.

In the operation of this embodiment the 100 sand is fed into the hopper 10 and carried outwardly to the pulley 37 where it is hurled downward into the flask. To secure the desired universal movement for the projecting end of the machine over the flask 105 the head is moved back and forth by sliding the beams 4 in the guides 3 and is swung from side to side around the pivot 2 as in the embodiment of Figures 1 to 7.

Figure 12 illustrates an alternative form 110 of bucket or impeller for the belt 36, which comprises straight or substantially straight projections 47 on the surface of the belt in front of which the sand is formed into wads by the compactor 48 which comprises 115 a paddle or blade 48^a swung from the pivot 48^b above the belt 36 so as to drag on the belt and compact the sand against the impellers 47 but which is free to slide over the top of the impellers 47. A weight or spring 120 may be provided for urging the blade 48^a into contact with the belt 36 if desired.

In compliance with the patent statutes, I have illustrated and described a preferred embodiment of my invention but it is to be understood that various modifications and changes can be made therein without departing from the spirit of the invention or the scope of the appended claims.

I claim:

1. In a molding machine of the type described, a projector, means to operate the projector, a supporting mast, a pivot and a slide supported on said mast, means extending through said slide and slidable therein for supporting the projector and means for conveying sand or other molding material from over said pivot, to the projector.
- 10 2. In a molding machine of the type described, a supporting mast, a pivot, and a slide supported on said mast, beams projecting through said slide and slidable therein, a projector at one end of the beams, means supported by the beams for driving the projector, and a conveyor supported by said beams for conveying the molding material to said projector.
- 15 3. In a molding machine of the type described, means for throwing the molding material into the flask with sufficient velocity to pack the same, means to support the throwing means, means to permit turning of the throwing means around said support as a pivot, means to permit said throwing means to be moved in a horizontal plane toward and away from said supporting means, means to convey molding material from over said supporting means to said throwing means, means on the opposite side of said supporting means to drive said throwing means, and a driving connection between said drive and throwing means.
- 20 4. In a molding machine of the type described, a support, a pivot adapted to turn about said support, a slide on said pivot, supporting means projecting through said slide, a projector at one end of said supporting means, a belt conveyor for conveying the molding material from over said pivot to the projector, and power means to operate said machine.
- 25 5. In a molding machine of the type described a vertical support, a pivot adapted to turn about said support, a pair of slides on said pivot, a pair of beams extending through said slides, a projector carried at one end of said beams, a conveyor for conveying molding material from over said pivot to said projector and means to drive said projector.
- 30 6. In a molding machine of the type described a vertical support, a pivot adapted to turn about said support, a pair of slides on said pivot, a pair of beams slidable through said slides, a deflector at one end of said beams, a belt conveyor supported on said beams, a plurality of buckets on said belt and means to drive said belt to convey molding material from over said pivot to the end of said beams and there, by the aid of said deflector, to hurl the molding material downward into a flask with sufficient velocity to pack same densely enough for molding purposes.
- 35 7. In a molding machine of the type described, a main support, a pivot supported thereby, a slide on said pivot, a horizontal projecting support, mounted in and slidable through said slide, whereby said horizontal projecting support may have universal movement in a horizontal plane about said pivot as an axis, a conveyor for conveying the molding material from over said pivot along said horizontal projecting support to a point remote from said axis and means for projecting the molding material downward from said point remote from said axis under sufficient velocity to pack same into the flask.
- 40 8. In a molding machine of the type described, a pivot and a slide, a pair of beams projecting through said slide, and adapted to be turned about said pivot and moved back and forth in said slide, a deflector supported by said beams and spaced from said pivot, an endless belt conveyor supported by and movable with said beams for conveying molding material from over said pivot to said deflector, a plurality of buckets on said conveyor and means to drive the conveyor with sufficient velocity to hurl the molding material downward from said deflector with sufficient velocity to pack the same densely into a molding flask.
- 45 9. In a molding machine of the type described, a pivot and a slide, a pair of beams projecting through said slide, and adapted to be turned about said pivot and moved back and forth in said slide, a deflector supported by said beams and spaced from said pivot, an endless belt conveyor supported by and movable with said beams, for conveying molding material to said deflector, a plurality of buckets on said conveyor means to compact the molding material into wads and means to drive the conveyor, to hurl the molding material downward from said deflector with sufficient velocity to pack the same densely into a molding flask.
- 50 10. In a molding machine of the type described, a pivot and a slide, a pair of beams projecting substantially horizontally through said slide and adapted to be turned about said pivot and moved back and forth through said slide, a pair of pulleys supported by said beams on opposite sides of said pivot, a deflector over one of said pulleys and spaced therefrom, a substantially horizontal belt conveyor extending over said pulleys, impellers on said conveyor, means to deliver molding material to the machine over said pivot and means to drive said conveyor to convey said molding material from the point of delivery to said deflector and there, by the aid of said deflector hurl, it downward into the flask.
- 55 11. In a molding machine of the type described, a pivot and a slide, a pair of beams projecting substantially horizontally through said slide and adapted to be turned about said pivot and moved back and forth through said slide, a pair of pulleys supported by said beams on opposite sides of said pivot, a deflector over one of said pulleys and spaced therefrom, a substantially horizontal belt conveyor extending over said pulleys, impellers on said conveyor, means to deliver molding material to the machine over said pivot and means to drive said conveyor to convey said molding material from the point of delivery to said deflector and there, by the aid of said deflector hurl, it downward into the flask.
- 60 12. In a molding machine of the type described, a pivot and a slide, a pair of beams projecting substantially horizontally through said slide and adapted to be turned about said pivot and moved back and forth through said slide, a pair of pulleys supported by said beams on opposite sides of said pivot, a deflector over one of said pulleys and spaced therefrom, a substantially horizontal belt conveyor extending over said pulleys, impellers on said conveyor, means to deliver molding material to the machine over said pivot and means to drive said conveyor to convey said molding material from the point of delivery to said deflector and there, by the aid of said deflector hurl, it downward into the flask.
- 65 13. In a molding machine of the type described, a pivot and a slide, a pair of beams projecting substantially horizontally through said slide and adapted to be turned about said pivot and moved back and forth through said slide, a pair of pulleys supported by said beams on opposite sides of said pivot, a deflector over one of said pulleys and spaced therefrom, a substantially horizontal belt conveyor extending over said pulleys, impellers on said conveyor, means to deliver molding material to the machine over said pivot and means to drive said conveyor to convey said molding material from the point of delivery to said deflector and there, by the aid of said deflector hurl, it downward into the flask.

- through said slide and adapted to be turned about said pivot and moved back and forth through said slide, a pair of pulleys supported by said beams on opposite sides of said pivot, a quadrant shaped deflector over one of said pulleys and spaced therefrom, means to adjust one of said pulleys toward and away from the other pulley, a substantially horizontal belt conveyor extending over said pulleys, impellers on said conveyor, means to deliver molding material to the machine over said pivot, and means between the pivot and said deflector to drive said conveyor to convey said molding material from the point of delivery to said deflector and there, by the aid of said deflector hurl it downward into the flask.
12. In a molding machine of the type described, a pivot and a slide, a pair of beams projecting substantially horizontally through said slide and adapted to be turned about said pivot and moved back and forth through said slide, a pulley supported by said beams at one side of said pivot, a motor with a rotating casing supported by said beams at the other side of said pivot, a deflector over said pulley and said motor casing and impellers on said conveyor.
13. In a molding machine of the type described, a pivot and a slide, a pair of beams projecting substantially horizontally through said slide and adapted to be turned about said pivot and moved back and forth through said slide, a pulley supported by said beams at one side of said pivot, a motor with a rotating casing supported by said beams at the other side of said pivot, a deflector over said motor casing and spaced therefrom, a belt conveyor extending over said pulley and said motor casing, impellers on said conveyor means to pack the molding material against said impellers and means to enclose said conveyor between said pivot and said deflector.
14. In a molding machine of the type described, a pivot and a slide, means to support a deflector for universal movement in a horizontal plane about said pivot as an axis, means to deliver molding material to said machine over said pivot and single means to convey said molding material from the point of delivery to said deflector in all positions of the same, and for there hurling the sand downward into the molding flask with sufficient velocity to pack same densely enough for metal founding.
15. In a molding machine of the type described, a pivot and a slide, means to support a deflector for universal movement in a horizontal plane about said pivot as an axis, means to deliver molding material to said machine, single means to convey said molding material from the point of delivery to said deflector in all positions of the same, and for there hurling the sand downward into the molding flask, and means for driving said conveyor at high velocity.
16. In a machine of the type described, a main supporting means, a pivot and a slide, a horizontal supporting means extending through said slide, a projector supported at one end of said horizontal supporting means, a motor supported at the other end of said horizontal supporting means, means extending between said motor and said projector for driving said projector, and means for conveying molding material from over said pivot to said projector.
17. In a machine of the type described, a main supporting means, a pivot and a slide, a horizontal supporting means extending through said slide, a projector supported at one end of said horizontal supporting means, a motor supported at the other end of said horizontal supporting means, a motor shaft extending between said motor and said projector for driving said projector, means for conveying molding material from over said pivot to said projector, and means for driving said conveyor from said motor shaft.
18. In a machine of the type described, a main supporting means, a pivot and a slide supported thereby, a horizontal supporting means extending through said slide and extending outward at opposite sides of said pivot, a projector supported at one end of said horizontal supporting means, a motor for driving said projector, and means for conveying molding material from over said pivot to said projector.
19. In a molding machine of the type described, a supporting mast, means for supporting a projector for pivotal movement about said mast, and for straight line movement toward and away from said mast, said supporting means being supported on and above said mast whereby to support said projection in approximately the horizontal plane of the top of said mast, means for driving said projector, and means for conveying molding material from over said mast to said projector.
- In testimony whereof I have affixed my signature to this specification.

NELSON LITTELL.
